UNITED STATES PATENT OFFICE.

AMANDUS WIGREN, OF ORNSKOLDSVIK, SWEDEN.

SUPPORT FOR LIFE-PRESERVERS.

1,224,819.

Specification of Letters Patent.

Patented May 1, 1917.

Application filed August 8, 1916. Serial No. 113,812.

To all whom it may concern:

Be it known that I, AMANDUS WIGREN, a subject of the King of Sweden, residing at Ornskoldsvik, Sweden, have invented new and useful Improvements in Supports for Life-Preservers, of which the following is a specification.

An object of the invention is to provide a support for life preservers, to secure the same against accidental displacement or removal from the side rail or other part of a vessel, dock or building, and at the same time permit of a person readily releasing the life preserver from its secured position.

Among other features the invention comprehends the provision of a suitable frame for attachment to the side rail or wall to support the life preserver and hold it against accidental displacement and from being battered away by high seas, suitable means being provided whereby at a moment's notice the life preserver can be released and placed in use.

The ordinary method now used for securing life preservers to the side rail of a ship is to lash the life preserver to the rail by means of suitable cord or rope, which, at the crucial moment, must be cut with a knife in order to release the life preserver. Even though lashed to the side rail of the ship in the latter method, a life preserver so secured, is oftentimes torn away by high seas and waves which persistently strike and wash over the side rail in severe weather. Further, when a life preserver is lashed with rope, as mentioned, it takes time to cut the rope and the desired implement for accomplishing this purpose is not always handy at the moment when a very short period of time may mean the saving of a life at sea.

My invention overcomes the above defects and provides for not only securing the life preserver against accidental removal but permits of readily and quickly releasing the life preserver without the use of tools, knives or other implements so that at a moment's notice, the life preserver can be released and placed in use to effect the desired result.

In the further disclosure of the invention reference is to be had to the accompanying drawing, constituting a part of this specification, in which similar charac-

ters of reference denote corresponding parts in all the views, and in which,

Figure 1 is an elevation showing the life preserver supported by means of my device,

Fig. 2 is a vertical transverse sectional view of the structure shown in Fig. 1,

Fig. 3 is a similar view showing the life preserver as it is released, and

Fig. 4 is a perspective view of the holding element.

Referring more particularly to the views, the numeral 10 indicates the side rail of the ship to which is secured, in any suitable manner, an inverted Y-shaped frame 11, preferably at its upper end terminating in a hook 12 which is suitably hooked over the upper bar 13 of the rail 10. At the lower ends of arms 14, forming a part of the frame 11 are eyelets 15 which swingingly support pieces 16 curved to fit around a life preserver 17, the said pieces having connection 75 with chains 18, which, in turn, are connected to a chain 19 having an end connected to a holding element 20, also curved to fit around life preserver 17.

A spring actuated latch 21 is arranged 80 upon the frame 11 and has a handle 22 projecting through a slot 23 in the frame so that the latch can be operated from the deck of the vessel, said latch including a vertically arranged bar 24, actuated upon by a 85 spring 25, arranged in a casing 26 with the upper end of the bar tapered at a point where it passes through a stirrup 27, and at which point a tongue 28 on the holding element 20 passes through the stirrup 27 and 90 is frictionally held in position by the bar 24 of the latch so that the holding element 20 will be locked in position to secure the life preserver against the side rail of the vessel.

Now when it is desired to release the life 95 preserver it is only necessary to press downwardly upon the handle 22 to move the latch against the action of the spring and thus it will be seen that the holding element 20 will be released, so that it can gravitate downwardly into an inoperative position, thus releasing the life preserver to permit the latter to fall away from the side rail and drop into the sea or to be grasped by a person on the deck and thrown out to the person in the 100 water.

From the foregoing description it will be seen that the device described is simple in

construction, consists of few and simple parts which can be cheaply manufactured and easily assembled and that the invention will effectively accomplish the purpose for 5 which it is intended and permit of carrying or throwing a life preserver to a person who has fallen into the water, in a very short space of time.

Having described my invention, I 10 claim:—

1. A support for life preservers comprising a Y-shaped frame, a latch on said frame movably supported pieces to fit around the life preserver, a holding element normally 15 fitting around the life preserver and connecting with the latch to be normally locked by the same and support the life preserver and a connection between said pieces and holding element.

2. A support for life preservers comprising

ing a frame, pieces mounted on the frame to fit around the life preserver, a holding element fitting around the life preserver, releasing means normally locking the holding element in position to secure the life preserver and means connecting the pieces with the holding element for releasing the former from holding position when the latter is released.

3. A support for life preservers embody- 30 ing a frame, a stirrup thereon, a U-shaped holding element for normally supporting the life preserver, a latch operable on the frame at a point below the stirrup, and an extension on the holding element adapted to 35 project into the stirrup and be normally engaged by the latch to secure the life preserver against removal from the frame.

In testimony whereof I affix my signature.

AMANDUS WIGREN.
